UNITED STATES PATENT OFFICE.

ERNEST REICH, OF CHICAGO, ILLINOIS, ASSIGNOR TO HILL PUMP VALVE COMPANY, OF CHICAGO, ILLINOIS, A CORPORATION OF ILLINOIS.

SEAL.

1,337,985.

Specification of Letters Patent. Patented Apr. 20, 1920.

Application filed July 14, 1916. Serial No. 109,300.

To all whom it may concern:

Be it known that I, ERNEST REICH, a citizen of the United States, residing at Chicago, county of Cook and State of Illinois, 5 have invented a new and useful Improvement in Seals, of which the following is a specification.

The invention relates to seals preferably used upon car doors, but adaptable to any 10 purpose wherever seals of this type are required.

The purpose of providing seals of this character consists in enabling the quick detection of tampering therewith since opening of the seal can only be effected by means of force and is attendant by visible signs of destruction.

The seals hitherto placed on the market, in spite of many endeavors to perfect the 20 same so as to meet practical requirements possess certain advantages which are obtained by the loss of others. While it is comparatively easy to construct a seal which in locked condition cannot be opened without mutilation, the objectionable features of most seals is found in the presence of a casing which formed at one end of a strip receives the other end thereof, thus rendering it difficult to detect whether attempts have 25 been made to open the seal.

It therefore constitutes the principal object of my invention to provide a seal with its parts accessible to inspection, and which in spite of this arrangement obviates any 35 possibility of tampering therewith, and renders opening thereof without mutilation entirely impossible.

A subsidiary object consists in so constructing the parts that in spite of the absence of a casing the locking elements are 40 not easily accessible to instruments or tools for the purpose of separating them, but may be freely inspected to ascertain surreptitious manipulation.

Additional objects embrace the provision 45 of a seal which may be readily closed without exerting great pressure; the adoption of closing elements which are partly covered by the strip from which they are stamped out; and the arrangement of an elongated opening in one of the tubular locking elements to facilitate closing of the seal.

It also constitutes an object of the invention to provide certain combinations and arrangements of parts which tend to enhance 55 the effectiveness and desirability of a device of this character.

With these and other objects in view that will be obvious as the description proceeds, the invention in several embodiments is described in the following specification and is specifically pointed out in the appended claims.

In the accompanying drawings—

Fig. 1 is a top plan view of a seal in 65 open position, made in accordance with the invention.

Fig. 2 is a sectional elevation.

Fig. 3 is a sectional elevation of a seal in closed position. 70

Fig. 3^A is a sectional elevation of a seal of known construction.

Fig. 3^B is a similar view of the seal in closed position.

Fig. 4 illustrates in sectional elevation a 75 modification of the seal in closed position. Fig. 5 is a top plan view of a further modified form of a seal which is equipped with an additional locking element adapted to oppose separation of the locking members. 80

Fig. 6 shows a sectional view of the seal.

Fig. 7 is a similar view with one locking member folded upon the strip preparatory to closing the seal.

Fig. 8 illustrates a sectional view of the 85 seal in closed position.

Fig. 9 is a top plan view of another modification.

Fig. 10 is a sectional view thereof.

Fig. 11 illustrates in section the closed 90 seal.

Fig. 12 illustrates in section a still further modification of the seal.

Fig. 13 shows an enlarged section through part of a seal shown in Fig. 9 and 95

Figs. 14 and 15 are sections on respective lines of Fig. 9.

Referring to the drawings, and particularly to Figs. 1 to 8, 1 designates a strip of tin or other suitable material or metal 100 which adapts itself readily to the requirements of seals. At one end of said strip a locking member 2 of tubular or other suitable or preferred form is stamped out. If

preferred or suitable the member 2 may be made separate and secured to the strip 1 in any approved or suitable manner. The locking member 2 at its upper extremity is bent 5 back upon itself to form a flange or flaring portion 3. As is obvious from Fig. 1 the opening 4 at the base of the flaring portion is formed elliptical or elongated for a purpose presently to be described. At the 10 other end of the strip at a suitable distance from the locking member 2 another locking member 5 is stamped out from, or may be made separate and secured to the strip 1. This member extends in a direction opposite to that of the other member 2 and is formed at its lowermost extremity with an upturned flange or bead 6. The locking members 2, 5 which may also be termed plug and socket members extend in vertical 15 direction with respect to the strip 1. In closing the seal the member 5 is turned clockwise until the flange 6 is above and in alignment with the flaring portion 3 of member 2. Thereupon slight pressure is exerted upon the member 5 until the bead 20 6 is forced through the opening 4 of the other member whereupon said bead engages the lower edge of the flaring portion and the seal is locked. The provision of the 25 elliptical or elongated opening 4 greatly facilitates the interlocking of the members as the short diameter of the opening is at least equal to the diameter of the flange and hence engagement of the parts takes 30 place at only two diametrically opposite points. In order to facilitate the folding of the strip and to predetermine accurately at which line the strip shall bend slots 35 7 and 8 are provided between the locking members to weaken the cross-section of the strip 40 on the bending lines.

It is apparent from Fig. 2 that by virtue of the arrangement of the members to extend in opposite directions from the strip 45 the latter covers the open side of the locking member 2. This feature is of vital importance as the strip prevents access to the engaging parts viz: the flaring portion 3 and the flange or bead 6. The open side 50 of the member 5 (Fig. 3) is not covered since it is impossible to insert there an instrument for the purpose of bending the flange 6 so that it forms an extension of its integral member whereby the locking members could be separated from one another. 55 The only opening which would permit the insertion of a tool to accomplish separation of the member is at the base of member 2 and here the strip 1 makes such attempts 60 futile.

Figs. 3^A and 3^B illustrate a seal of known construction where the locking members 2' and 5' are arranged at the same side of the strip 1'. It is obvious that the opening

at the base of member 2' affords ready 65 access to the engaging parts and therefore the temptation is present to tamper with the seal.

As a further means of increasing the safety of the seal the locking member 5 70 is provided with a flaring portion 6' which obviates the possibility of inserting a flat instrument between the locking members.

The modification illustrated in Fig. 4 is distinguished from the form shown in Figs. 75 1 to 3 by the fact that a strip 9 of suitable length is folded to form a loop with its ends interposed between the locking members. The strip ends are provided with openings 80 10 of sufficient diameter to permit passage 85 of the plug member 5 upon closure of the seal and at which time they are placed in alignment with one another and with the locking members.

Referring to Figs. 5 to 8, 11 designates a 85 strip of tin or other suitable material which in contradistinction to the first form is of greater length. In this case the tubular member 12 extends upwardly and includes 90 also a flaring portion 13 which is provided with an elliptical or elongated opening 14. At a suitable distance another locking member 15 extends downwardly from the strip 11. This member is also bent back upon itself to form an annular flange or bead 16 and is provided with a flaring portion 21 at its base. Manifestly the two locking members can have other than tubular form and instead of being stamped out from the strip they can be made separate and fastened thereto in any suitable or approved 95 manner.

At the other end of the strip 11 an additional locking member 17 is stamped out in the form of a truncated cone having the 105 larger diameter at its base. If desired this member may be made separate and may be secured to the strip in any suitable or approved manner. In order to enhance the resiliency of the member 17 a plurality of 110 slots 18 are provided, but if desired they may be dispensed with without affecting the operativeness of the seal. From the drawing it is apparent that the slots may be made deep enough to obtain a plurality of tongues 115 which act independently from one another. To further increase the resiliency of the additional locking member 17 a bead 22 is stamped out therefrom from its body portion close to its base.

Between the members 12 and 15 a portion 120 of the strip is cut out as at 19 and between the members 15 and 17 two similar cut-out portions 20 are provided.

In order to fold the seal the member 12 125 is turned counter-clockwise to the position shown in Fig. 7 so as to engage with its base portion the under side of the strip 11.

Thereupon the opposite end of the strip is folded in clockwise direction so as to place the member 17 in circumferential engagement with the locking member 15 and finally 5 the member 12 together with the contiguous end of the strip is again bent about the remote transverse edge of a cut-out portion 19 so as to force the flaring portion 13 into engagement with the flange 16 of member 10 15 whereby the seal is locked.

From the foregoing it is obvious that the open side of the member 12 corresponding to member 2 of the first described modification is again covered so as to prevent access to 15 the engaging parts with a pair of pliers or other instrument for the purpose of surreptitiously forcing the locking members apart. The function and purpose of member 17 will be explained in connection with the 20 subsequently described modification but it may be briefly stated that it serves as an additional locking means to prevent relative movement of the locking members or plug and socket members 12 and 15 upon 25 manipulation. The flaring portion 13 having the elliptical or elongated opening 14 engages the annular flange 16 of member 15 at only two points upon closing the seal which thus may be effected with slight 30 pressure.

The seal illustrated in Figs. 5 to 8 requires three distinct folding movements to be closed and in order to reduce the number of motions the further modification 35 presently to be described is constructed with this end in view. The locking strip 23 is provided with the socket and plug members 24, 26, the former having the flaring portion 25 while the latter is formed with the flange 40 27 and the flaring portion 31 at its base. The locking member 28 is slotted and is provided with the annular bead 29 as indicated in Figs. 9 and 10. The plug member 26, however, is arranged at the end of a 45 tongue 30 stamped out from an intermediate portion of the strip 23. In closing the seal the member 28 is turned in counter-clockwise direction until it is seated on the flaring portion 25 of the socket member 24 50 thereupon the plug member 26 is turned clockwise until it is above and in alignment with the socket member. By exerting a slight pressure the plug and socket members are then interlocked.

55 The function of the member 28 is best understood by reference to Fig. 13. It may be assumed that a knife blade or any other flat bar or the like is introduced into the space 32 confined between the members 26 and 28. Irrespective of the direction in which the blade is turned it is apparent that a downward pressure acts on the member 28 whereby the same is forced into intimate circumferential engagement with the middle

portion of the member 26, thus preventing 65 the same from being raised and from exerting an undue pull on its flange 27 by virtue of the engagement between said flange and the edge of the flaring portion 25 of the socket member. If on the other hand a 70 blade is inserted into the space 32 confined between the members 28 and 24, an upward pressure acts on the member 28 forcing it into intimate circumferential engagement 75 with the plug member and locking the same in place. Attention is called to the fact that the plug member is provided with a flaring portion 31 in order to limit the space into which a blade may be inserted when tampering with the seal. When, for instance, forcing a flat object between the members 26 and 28 in the space 32 the flat instrument will be arrested by the slanting 80 wall of the plug member whereby only a small leverage can be secured when attempts 85 are made to pry the seal open.

The modification illustrated in Fig. 12 differs from the modification illustrated in Figs. 9 to 11 by the omission of the additional locking member 28 and the respective end of the strip is provided with a plug member, while an opening 34 having a sufficient diameter to loosely surround the plug member and to permit the passage of the latter upon closure of the seal without any resistance whatever, is provided on the stamped out tongue.

The sectional views indicated in Figs. 14 and 15 disclose a method of forming the elongated hole in the flaring portion 25 of 100 the socket member 24. It is readily seen that the wall of the flaring portion forms an angle α on the line 14—14 of Fig. 9 with the horizontal plane intersecting the lowermost edge of the flaring portion while a 105 different angle β is formed on the line 15—15. From this it is obvious that if for instance angle α is smaller than the angle β an elongated opening is obtained so that upon closure of the seal the plug member 110 engages the socket member only at two diametrically opposite points.

The form of the opening in the flaring portion of the socket member may be varied and in Fig. 5 the flaring portion of the 115 socket member is provided with a circular opening provided in transverse direction of the strip with arcuate cut-outs whereby an elongated opening is obtained without unduly removing material.

When attempts are made to open the seal it has been found by a series of break tests that it is impossible to force the seal proper apart unless the force applied is so great that it exceeds the strength of the material, 125 in which case the locking members are torn about and are so completely destroyed that resetting of the members to hide their mu-

tilated condition is impossible. In view of the fact that the strip is in the form of a loop it is clear that the force applied to the seal is more evenly distributed over the strip than over the seal proper, and for this reason it may occur that upon fraudulent manipulation the seal may break while the strip remains intact. To avoid these possibilities I have found it advisable to arrange 10 a plurality of slots throughout the length of the strip and to this end in view I have provided the triangular cut-out portions 20 in Fig. 5, while in the modification shown in Fig. 9 a similar cut-out portion 35 is arranged which in addition to the cut-out portion given by the stamped-out tongue effectively weakens the strip.

I am aware that various changes and modifications may be made without departing from the spirit of the invention and for this reason I want to avail myself of any changes, alterations, modifications and departures which fall within the scope of my invention as pointed out in the appended 25 claims.

I claim:

1. In a seal, a tubular member having a flange, a second tubular member having means for interlocking with said first named 30 member, and a strip connecting said members, said members being arranged one on each side of said strip, the end portion of said strip being folded upon itself to afford a closure for the open base portion of the 35 appertaining tubular member.

2. In a seal, a strip and a pair of tubular members having flanges and being arranged on said strip, said members being adapted 40 to interlock upon being brought into engagement by pressure, said strip being folded upon itself preparatory to locking said members, to afford a closure for the base opening of one of the members.

3. In a seal, a strip, a tubular member, 45 and a second tubular member provided with means for interlocking with said first named member, said members extending in opposite directions with respect to each other and being arranged one on each side of said strip, the end portion of said strip being folded upon itself to afford a closure for the base opening of the appertaining tubular member.

4. In a seal, a strip, a socket member arranged on one side of said strip and extending upwardly therefrom, and a plug member arranged on the other side of said strip at a distance from said socket member and extending downwardly from said strip, said 50 members being adapted to interlock upon being brought into engagement by pressure, the end of said strip being folded upon itself to afford a closure for the base opening of said socket member.

5. In a seal, a strip, tubular locking members adapted to interlock upon being brought into engagement, said tubular members being arranged one on each side of said strip whereby the strip is folded prior to interlocking the members so as to form 70 a closure for the base opening of one of said tubular members.

6. In a seal, a socket member, a plug member provided with means for interlocking with said first named member, and a flexible element connecting said socket and plug members, said element being folded upon itself to form a closure for the base opening of said socket member upon closure 75 of the seal.

7. A seal comprising a socket member provided with locking means, a plug member provided with means for interlocking with the locking of said first named member, a flexible element to which said first and second named members are secured, and an additional locking element for preventing separation of said members, after they are interlocked, said members extending in opposite directions from said element.

8. A seal comprising a socket member provided with locking means, a plug member provided with means for interlocking with the locking of said first named member, a flexible element to which said first and second named members are secured, and an additional locking element for preventing separation of said members, after they are interlocked, said members extending 95 in opposite directions with respect to each other whereby the locking means are arranged on opposite sides of said element.

9. A seal comprising a socket member, provided with locking means, a plug member provided with means for interlocking 100 with the locking of said first named member, a flexible element to which said first and second named members are secured, and an additional locking element for preventing separation of said members, after they are 110 interlocked, said members extending upwardly and downwardly respectively from said element, said element being folded with an end portion thereof over the open base portion of said socket member.

10. A seal comprising a socket member provided with locking means, a plug member provided with means for interlocking with the locking of said socket member, an additional locking member adapted to be 120 interposed between said members, and a flexible element serially connecting all of said members, said first two members being arranged one on each side of said element and extending in opposite directions with respect to each other.

11. A seal comprising a socket member, a plug member provided with means for

- interlocking with said socket member, an additional locking member adapted to be interposed between said members to oppose separation of the same, and a flexible element serially connecting all of said members, said first two members extending in opposite directions, said plug member extending in slanting direction with respect to said element.
12. A seal comprising a tubular member having a flaring portion forming an elongated opening at its smaller end, a locking member provided with means for interlocking with said tubular member, additional locking means adapted to be interposed between said first two members to oppose separation of the same, and a strip connecting all of said members, said first two members extending in vertical and slanting direction respectively with respect to said strip and being arranged one on each side thereof.
13. A seal comprising a tubular member having a flaring portion, the wall of said flaring portion forming different angles with respect to a horizontal plane intersecting its lower-most edge, a locking member provided with means for interlocking with said tubular member, additional locking means adapted to be interposed between said first two members to oppose separation of the same, and a strip connecting all of said members, said first two members extending in vertical and slanting direction, respectively, with respect to said strip and being arranged one on each side thereof.
14. A seal comprising a strip, a socket member arranged at one end of said strip, a locking member provided at the opposite end of said strip, said strip being formed intermediate its ends with a stamped out tongue, and a plug member formed on said tongue and means for securing the socket and plug members together.
15. A seal comprising a strip, a socket member arranged at one end of said strip, a tongue stamped out from an intermediate portion of said strip, a plug member arranged at the end of the tongue and provided with means for interlocking with said socket member, and a locking element adapted to be interposed between said socket and plug members to oppose separation of the same, said socket and plug members extending in opposite directions with respect to said strip.
16. A seal comprising a strip, a socket member arranged at one end of said strip, a tongue stamped out from an intermediate portion of said strip, a plug member arranged at the end of the tongue being provided with a flaring portion at its base and with means for interlocking with said socket member, and a locking element adapted to be interposed between said socket and plug members to oppose separation of the same, said socket and plug members extending in opposite directions with respect to said strip.
17. As an article of manufacture, a seal comprising a strip, a socket member formed at one end of said strip and extending upwardly therefrom, a tongue stamped out from said strip, a plug member arranged on said tongue and extending downwardly, and a locking member at the other end of said strip adapted to be interposed between said socket and plug members to oppose separation of the same, said socket and plug members being provided with means for interlocking.
18. As an article of manufacture, a seal comprising a strip, a socket member formed at one end of said strip, a tongue stamped out from said strip, a plug member arranged at the end of said tongue, and a locking member at the other end of said strip adapted to be interposed between said socket and plug members to oppose separation of the same, said locking member being formed with slots and with a bead at its base, said socket and plug members being provided with means for interlocking.
19. As an article of manufacture, a seal comprising a strip, a socket member formed at one end of said strip and extending vertically and upwardly therefrom, a tongue stamped out from an intermediate portion of said strip, a plug member arranged at the end of the tongue and extending downwardly and in slanting direction with respect thereto, said socket and plug members being provided with means for interlocking and a locking member at the other end of said strip adapted to be interposed between said socket and plug members to oppose separation of the same, said locking member being formed with slots and with a bead at its base, substantially as described.
20. A self-locking seal, comprising a flexible sheet-metal shackle provided at a short distance from one end with an externally-flanged locking-stud and having the metal at said end forming a laterally-projecting cup, with the bottom wall thereof perforate and dished inwardly to afford an internal locking flange, the end portion of the shackle being folded upon itself so that a portion of the shackle affords a wall covering the open base-portion of the cup, said shackle having a perforate end adapted to engage said stud and lie beneath the bottom of said cup when the seal is locked.
21. In a seal, a tubular member, a second tubular member having means for interlocking with said first named member, a flexible element connecting said members, and means for closing the base opening of one of said members, said closing means be-

- ing formed integral with said flexible element.
22. In a seal, a tubular member, a second tubular member having means for interlocking with said first named member, a flexible element connecting said members, and means for closing the base opening of one of said members, said tubular members and said closing means being formed integral with said flexible element.
23. A seal comprising tubular locking

members adapted to interlock upon being brought into engagement, a flexible element interconnecting said tubular member, and means for closing and preventing direct access to the interlocking parts of said member, said means being formed integral with said flexible element.

In testimony whereof I have herewith set my hand.

ERNEST REICH.
